KEY CASE

John M. Mullin, 1474 Maple St., Barberton, Ohio

Filed Feb. 6, 1961, Ser. No. 63,836

Term of patent 14 years

(Cl. D87—3)

Fig. 1

Fig. 4

Fig. 2

Fig. 3

Fig. 5

Fig. 6

Fig. 7

FIG. 1 is a top plan view of a key case, showing my new design;

FIG. 2 is a side elevational view thereof;

FIG. 3 is a right end elevational view thereof;

FIG. 4 is a left end elevational view thereof;

FIG. 5 is a bottom plan view thereof;

FIG. 6 is a longitudinal vertical section of FIG. 2; and

FIG. 7 is a perspective view thereof in operably open condition.

The broken line showings of a beaded chain and keys in the various figures are for illustrative purposes only.

I claim:

The ornamental design for a key case, substantially as shown and described.
